UNITED STATES PATENT OFFICE

HARLSON H. DODD, JR., OF LUZERNE, IOWA

DOOR LATCH

Application filed February 16, 1927. Serial No. 168,561.

The object of my invention is to provide a door latch of simple, durable, and comparatively inexpensive construction.

A further object of my device is to provide a latch for doors or gates particularly of the sliding type but the device can also be used on swinging doors and gates as well.

Still a further object is to provide a latch which, when applied to a sliding door, will have a tendency to engage more firmly in an eye which is secured to the frame of the door.

Still a further object is to provide such a latch which can be secured to the door in position to move by gravity to a position where no parts of the device project beyond the edge of the door when the door is unlatched.

Still a further object is to provide means on the latch for utilizing a padlock for locking the latch against being opened.

With these and other objects in view, my invention consists in the construction, arrangement and combination of the various parts of my device, whereby the objects contemplated are attained, as hereinafter more fully set forth, pointed out in my claim and illustrated in the accompanying drawings, in which:

Figure 1 is a perspective view of the parts embodying my latch.

Figure 2 is an elevation showing the latch attached to a door and in latched position.

Figure 3 illustrates the device applied to a door and in unlatched position; and

Figure 4 is an enlarged elevation of the device showing the use of a padlock to prevent the latch from being unlatched.

On the accompanying drawings I have used the reference numeral 10 to indicate a supporting bar. The supporting bar 10 is formed with a pair of openings 12 for the purpose of receiving screws or bolts whereby the supporting bar is secured to a door or a door frame.

Figure 2 illustrates the supporting bar 10 secured to a door 14 by bolts 16.

Pivotedly mounted on the supporting bar 10 is a latch bar 18. The latch bar 18 is rotatably mounted on a rivet or the like 20 which extends through both the supporting bar 10 and the latch bar 18. A washer 22 is

interposed between the latch bar and the supporting bar for the purpose of preventing any binding of the parts. It is, of course, understood that the rivet 20 is riveted sufficiently loose for the purpose of allowing free pivotal movement of the latch bar 18 on the rivet 20.

The latch bar 18 is formed with a notch 24, the side 26 of which is formed at an angle relative to the bar 18. The purpose of so forming the side 26 of the notch 24 will hereinafter be more fully described.

The outer end of the latch bar 18 is cut narrower than the body portion thereof and is bent back upon itself for forming a handle member 28. The end is then riveted to the body portion of the latch bar 18 by means of a rivet 30 whereby a very satisfactory handle is formed.

A downwardly projecting hook member 32 is formed beyond the notch 24. The hook member 32 is provided with an opening 34 for receiving a padlock.

The hook member 32 is designed to engage an eye member 36 which is substantially angle shaped and is provided with openings 38. The eye member 36 is secured to the door frame or the door as the case may be by means of bolts or the like 40 extending through the openings 38. The upper outwardly projecting portion of the eye member 36 is formed with a slot opening 42 for the purpose of receiving the hook member 32 of the latch bar 18.

The supporting bar 10 and the eye member 36 are attached to a door and frame 44 of a barn or the like as clearly illustrated in Figures 2 and 3 of the drawings. It will be noted that the supporting bar 10 is spaced from the edge of the door 14 so that when the latch bar 18 is in unlatched position it will by gravity hang downwardly and will not present any parts projecting beyond the edge of the door. This position is clearly illustrated in Figure 3 of the drawings. The desirability of such construction lies in the fact that any projecting parts are subject to catching harness on horses as they pass into the barn or the like.

The parts 10 and 36 of course, may be re-

versed with the eye member 36 mounted on the door 14 and the latch bar 18 mounted on the door frame 44. In either case, the operation would be the same.

5 It will be noted that the slanting side 26 of the notch 24 when the hook member 32 is inserted through the opening 42 will have a tendency to pull the latch bar 18 downwardly if the door 14 is moved away from the door frame 44 when the latch is in latched position. This prevents any possibility of the latch coming unlatched when an attempt is made to open the door without unlatching it.

10 15 If desired a padlock 46 can be secured through the opening 34 of the hook member 32 after the latch 18 has been moved to latched position. The use of a padlock in this manner is clearly illustrated in Figure 20 1 of the drawings.

25 From the foregoing description it is obvious that I have provided a latch which in normal unlatched position will not present any edges or corners to be caught on objects passing through the barn door opening. Means has been provided to prevent accidental unlatching of the latch bar 18 from the eye member 36 when an attempt is made to open the door.

30 35 Some changes may be made in the construction and arrangement of the various parts of my invention, without departing from the real spirit and purpose of my invention, and it is my intention to cover by my claim any modified forms of structure or use of mechanical equivalents, which may be reasonably included within their scope.

I claim as my invention:

40 A door latch comprising a supporting bar, a latch bar of flat bar material pivoted thereto, a notch in said latch bar adjacent the end thereof, whereby a downwardly extending hook is provided, an eye member for said hook, the side of said notch farthest from the pivotal point of said latch bar being cut at an angle whereby pull on the latch bar tends to maintain the hook within said eye member and a handle for said latch bar comprising a portion of the bar beyond said hook 45 50 redoubled upon and secured to itself.

Des Moines, Iowa, February 8, 1927.
